VARIABLE SIGNAL TRANSMITTING
STATION

Clarence E. Beach, Binghamton, N. Y.

Application April 19, 1947, Serial No. 742,722

10 Claims. (Cl. 177—378)

1

This invention relates to variable signal transmitting stations, and is particularly suited for embodiment in stations of the type exemplified by so-called "municipal fire alarm boxes."

Each such fire alarm box ordinarily consists of an outer case comprising a door or cover and containing an inner case in which mechanism is mounted for formulating a predetermined code signal which characterizes the locality where the box is installed (hereinafter sometimes referred to as "location-code") together with a manual key for sending special calls, and a tap bell or other signal manifester.

The signal keys which have been provided in fire alarm boxes are utilized for sending various special signals and calls, including so-called "fire-out signals" and "test signals"; but the most important occasion for using such keys arises when a department officer at a fire decides that added assistance should be summoned.

In other words, certain of the calls for which such keys are intended are of even greater importance than the locality-indicating calls which are initiated by ordinary "pulling" of a box by a member of the general public.

It is, therefore, an important object of this invention to provide means for causing the formulation of variable special calls, which means will serve to safeguard such calls during various faulty conditionings of the associated circuit, to an extent as great as that obtained by location-code transmitting mechanisms having characteristics such as contemplated by my Patent No. 1,999,859, granted April 30, 1935.

It is another object to provide means for formulating such special calls in a manner such that control will be effected of at least a portion of the circuit from the originating box in one direction or the other to headquarters notwithstanding a concurrent or previously started signal from the same or another box.

A preferred form of signal transmitting station according to my invention may include a signal or alarm box in which certain of the mechanisms are installed, electrical conductors for providing a normally closed main signaling circuit and a normally isolated branch circuit, a signaling sender means, as for example a finger hold dial which is manually operable for selectively effecting formulation of diverse groups of code signaling impulses, the sender means comprising impulse formulating contacts having connections with the main and branch circuits, spring jacks serially connected in the main circuit, a cover mounted on the box and positionable for ob-

2

structing manual actuation of the signal sending means, a switching means operably connected with the main and branch circuits, means connected to said cover for actuating the switching means to different positions, the connections between the respective circuits and the switching means being effective for including either said contacts or said jacks in said branch circuit but only when said cover is in an unobstructive position with respect to said signal sender means, the switching means also being effective when said cover is in an obstructive position with respect to the signal sender means to provide in connection with a suitable conductor a shunt in the main circuit around the formulating contacts.

Means is also advantageously provided for yieldably retaining the cover in a position intermediate of the positions referred to above whereby the means for actuating the switching means effects circuit conditions differing from those established by positioning the cover either in its fully closed or obstructive position or in its fully open or unobstructive position.

The apparatus of the present invention also advantageously includes circuit controlling mechanism which will effect a change in the condition of the circuit of an impulse sender, e.g., to displacement of a cover for the sender from its obstructive position which circuit change is of a character such that if a signal is in course of formulation in the sender circuit (as from some other sender) at the time when the cover is withdrawn, a conditioning of such circuit will be established to cause suspension of the formulation of the signal of the distant transmitter, in at least a portion of the main sender circuit, and will effect reservation of at least that portion of the circuit for the signal of the associated sender.

Additional objects and advantages of this invention will become apparent to those skilled in this art by a study of the following description and claims, taken in connection with the drawings showing illustrative embodiments of the invention, wherein

Fig. 1 is a fragmentary elevation of a well-known type of fire alarm box transmitting station, with an embodiment of this invention applied thereto, and showing the hinged cover over the variable signal impulse sender in closed position;

Fig. 2 is an elevation of the parts shown in Fig. 1, with the hinged cover in open position;

Fig. 3 is a fragmentary elevation of the inner side of the inner door of Figs. 1 and 2, with a portion of the rear protective cover or can broken

away to show an arrangement of circuit conditioning contacts suited for accomplishing certain functional results;

Fig. 4 is a cross-sectional view of the inner door of Figs. 1, 2, and 3, taken approximately along the line 4—4 of Fig. 3, showing the hinged cover in closed position, and indicating the resultant positioning of the conditioning contact mechanism;

Fig. 5 is a view similar to Fig. 4, showing the hinged cover open, with resultant change in the positioning of the conditioning contact mechanism;

Fig. 6 is a schematic diagram of one of the more simple arrangements of current paths between parts such as are shown in Figs. 3, 4, and 5, in association with a signaling circuit suitable for response thereto;

Figs. 7 through 14 show a modified arrangement of contacts, and operating mechanism therefor, which arrangement is suited for accomplishment of results diverse from those obtained by use of the arrangement shown in Figs. 3 through 6; and in which

Fig. 7 is a fragmentary elevation, similar to that of Fig. 3;

Figs. 8, 9 and 10 are cross-sectional views of the inner door of Fig. 7, taken approximately along the line 8—8 of Fig. 7, and, respectively, showing the hinged cover fully closed, partially and fully open, and indicating the resultant positionings of the conditioning contact mechanism;

Figs. 11, 12, and 13 diagrammatically indicate the positionings of the contact cylinder with relation to the conditioning contacts of Figs. 8, 9, and 10, respectively; and

Fig. 14 is a schematic diagram of an arrangement of current paths between parts such as shown in Figs. 7, 8, 9, 10, 11, 12, and 13, for producing results differing from those obtainable by the arrangement shown by Fig. 6.

Description, Figs. 1-6

Referring to Figs. 1, 2, and 3, portions of the outer housing of a well-known type of fire alarm box are indicated at 21, 21, together with an edge view of the open outer door 23.

The inner case 25 has the inner door 27 secured thereto by hinges, such as 31. Said door is provided with an operating knob 29, secured thereto by the screw 39.

An opening 33 is provided for a starting or "pull" handle 35, which is associated in a usual manner with a suitable location-code signaling mechanism (not shown).

A cover member 41 is secured to the inner door 27 by the hinges 43. Said cover has a handle 45, also a boss 47 which may be engaged by a similar boss 48 carried by the outer door 23 (see Fig. 4) for at times assuring obstructive positioning of said cover as will be hereinafter more fully explained.

A variable signal impulse sender is carried by the door 27. This sender comprises a finger hold dial 51 and a finger stop 53, together with contacts operable responsive thereto for governing interconnection between three conductors in a manner which will presently be explained in greater detail. One arrangement of the contacts operable responsive to said dial 51 is generally indicated by dotted lines at 55 in Fig. 3, and is shown in greater detail in Fig. 6 as comprising the contacts 91, 93 and 95 and the actuator 97, all of which will be hereinafter more fully described: Another arrangement of such contacts is generally indicated by dotted lines at 55' in

Fig. 7, and is shown in greater detail in Fig. 14 as comprising the contacts 91', 93' and 95' and the actuator 97'.

Various well-known types of impulse sender mechanisms may be employed. Inasmuch as the details of such mechanisms form no part of this invention, none of such details are indicated in the drawings, other than the conventional dial 51, the finger stop 53, and the contacts 55 or 55'; together with a rear cover or cap 57 for enclosing suitable operating mechanism. Said dial is so situated with reference to the hinged cover 41 as to be rendered inaccessible when said cover is in closed position.

15 A cam comprising the portions 61 and 65 moves with the cover member 41 for actuating a lever 63. The portion 61 of said cam has a slot 67 formed therein (see dotted lines, Figs. 2, 3, 4, and 5). A wall 69 at one side of said slot provides a continuation of the periphery of the cam 65, and the other side of said slot provides an internal cam surface 71.

16 A roller 73, carried at one end of said lever 63, is engaged by the cam surfaces 69 and 71. The contact cylinder 75 is carried by the other end of the lever 63, but is insulated therefrom.

17 Said cylinder 75, together with flexible contacts 77, 77 and 79, 79, provide circuit conditioning contacts suited for use in systems in which it is desired to obtain operating results which will be hereinafter more fully set forth.

18 The flexible contacts 77, 77 are so positioned that the free ends thereof will be engaged by the cylinder 75 when the arm 63 is positioned by engagement of the roller 73 by the cam portion 65 or the external cam wall 69 which is adjacent thereto (see dotted position a in Fig. 6); and the flexible contacts 79, 79 are so positioned that said cylinder 75 will engage the free ends thereof when the lever 63 is positioned by engagement of said roller 73 by the internal cam surface 71 when the cover 41 is fully closed (see dotted position c in Fig. 6).

19 The parts are so proportioned that said cylinder 75 may be positioned intermediate said contacts 77 and 79 (see dotted position b in Fig. 6), and so that when said cylinder 75 is in position c (where it engages the contacts 79, 79, resultant from full closure of the cover 41) the clearance 20 between said cylinder and said contacts 77, 77 will be such that the path of any discharge of lightning or other static current from one to the other of said contacts 77, 77 will be unlikely to include said cylinder 75.

21 From the foregoing, it will be seen that a current path is provided for inclusion in the external circuit, which path serially connects the jacks which are generally indicated at 81 and 83 with the formulating contacts 91 and 93, respectively.

22 The catch 99 which cooperates with a suitably positioned depression in a surface of the cam 61, provides means for indicating to the user when the cover 41 is positioned for causing placement 23 of the cylinder 75 out of engagement with both the contacts 77, 77 and the contacts 79, 79 (see dotted position b in Fig. 6).

24 One of the more simple applications of this invention is diagrammatically shown in Fig. 6. 25 For purposes of illustration, the contacts thus far described are here shown in association with a circuit arranged in accordance with my Patent No. 2,034,017, dated March 17, 1936, for Multi-conductor Signaling System.

26 The normal battery NB, the line signal mani-

testing ground battery GB, the instruments LI, GI and EI, and the rectifiers IR' and IR'' correspond with instrumentalities similarly designated in said patent, to which reference is had. The line signal manifesting instruments LI, GI and EI, may be of various types well-known to persons skilled in this art; for example, such as that disclosed in Patent 1,920,237, dated August 1, 1933, to Clarence E. Beach and Foster E. Weld, for Signal Recorder.

Impulse sender contacts such as those generally indicated at 55, in Fig. 3, are here shown as comprising a flexible contact 91 which ordinarily rests against the relatively fixed contacts 93 and 95. Said contact 91 is subject to actuation by the insulating actuator 97. Such actuator may be governed in a well-known manner by any one of several types of mechanism, responsive to manipulation of the dial 51, for the purpose of effecting momentary interruptions of the usual connection between said contacts.

A cover or can 59 (shown partly broken away in Fig. 3) is carried by the inner side of the door 27, for the protection of the circuit conditioning contacts 75, 77, 77, 79, 79 and the governing mechanism associated therewith.

Spring jacks such as those generally indicated at 81 and 83 in Fig. 6, are carried by the inner door 27, for receiving plugs, such as may be associated with portable telephone sets. The portals 85 and 87 of said jacks are disposed behind the hood 29 shown in Figs. 1 and 2, and are there indicated by dotted lines. The terminals of said jacks project from the rear side of the inner door 27, as indicated at 38, in Fig. 3.

The spring jack 81 is serially connected between contact 91 and one of the conditioning contacts 79, and jack 83 is serially connected between fixed contact 93 and the other conditioning contact 79.

One of the conditioning contacts 77 is connected to the ground (or other common return conductor), and the other of said contacts 77 is connected to the fixed contact 95.

The impulse sender contacts 91, 93, and 95, the conditioning contacts 75, 77, 77, 79, 79, and the spring jacks 81, 83 are shown associated with code transmitting mechanism (for the location-code signal 23) schematically indicated at T' in a fire alarm box case indicated by the dotted line S1.

One of the terminals of the spring jack 81 (together with the associated one of the conditioning contacts 79, 79) is connected to one of the normally closed signal formulating contacts of the transmitter T'. Another of the contacts of said transmitter is connected to the portion of the external circuit leading toward the instruments EI and GI. The other side of the external circuit (which leads toward the instrument LI) is connected to the other of the conditioning contacts 79 and to that terminal of the spring jack 83 which is associated therewith.

Another fire alarm box or transmitting station S2 is shown connected in the circuit between the station S1 and the responsive instruments EI, GI.

The station S2 comprises transmitting mechanism schematically indicated at T'' for the location signal 21.

It will be understood that other stations may be similarly connected in the circuit at one side and the other of the station S1.

Operation, Figs. 1-6

Ordinarily, the outer door 23 and the cover 41

are closed. The boss 43 carried by the outer door then engages the boss 47 carried by the cover for maintaining said cover in fully closed position. Such positioning of said cover, acting through the cam 61 and the lever 63, causes the cylinder 75 to rest against the contacts 79, 79, as shown in Fig. 4 and indicated at c in Fig. 6; thereby to establish a shunt path for the fire alarm circuit around the jacks 81 and 83 and around the signaling contacts 91 and 93. While the parts are thus positioned, the current path from contact 95 to the ground (or other common return conductor) is interrupted at the contacts 77, 77.

When it is desired to send a special call, the outer door 23 should be opened, and the cover 41 should be moved to open position, as indicated in Figs. 2 and 5. Such movement of said cover 41 will cause the cam 61 to act through the lever 63 to move the cylinder 75 out of engagement with the contacts 79, 79 and into engagement with the contacts 77, 77, as shown in Fig. 5, and as also indicated by dotted circle a in Fig. 6.

Engagement of the contacts 77, 77, by the cylinder 75 at a time when the associated circuit is otherwise normally conditioned, will establish parallel current paths as follows:

One of these paths extends from a terminal of battery NB, through line signal manifesting instrument LI, jack 83, contacts 93, 91 and 95, one of the contacts 77, cylinder 75, the other contact 77, ground connection at the active signal station and the earth, ground connection at central office, ground battery GB, to other terminal of battery NB.

The other parallel path extends from a terminal of battery GB through line signal manifesting instrument GI and rectifier IR' (the path through line signal manifesting instrument EI being blocked in this direction to current by the rectifier IR'') from the rectifier IR' through signal station S2, through closed contacts of location-code transmitter T', through jack 81, contacts 91 and 95, one of the contacts 77, cylinder 75, the other contact 77, thence through station ground connection and the earth to headquarters ground connection of other terminal of battery GB.

Establishment of these parallel paths will render the instruments GI and LI responsive to such signals as may be formulated by actuation of the contacts 55 of station S1.

Such signal formulating actuation of said contacts 55 may be accomplished by operation of the dial 51 in the manner corresponding to usual practice in making telephone calls with machines switching systems.

For example, if the call 238 is to be transmitted, the user will first place his finger in the opening numbered "2" in the dial 51, and rotate the dial until his finger reaches the stop 53. He should thereupon remove his finger from the dial and permit the mechanism to operate to formulate two signaling impulses in the parallel paths for causing response of the line signal manifesting instruments GI and LI. The dial 51 should then be correspondingly actuated to effect the formulation of signals 3 and 8.

Should one or the other of the parallel paths just referred to be ruptured or subjected to formulation of some other signal, continued effectiveness of the other of such paths will, nevertheless, assure that the one of the instruments GI, LI which is connected in the unimpaired path

will respond to signals formulated by the contacts 55, for reasons more fully explained in my aforementioned Patent No. 2,034,017.

For example, if the current path is broken at or adjacent the station S2, the actuation of the dial of station S1 will not result in response of either the line signal manifesting instrument GI or the instrument EI. However, the instrument LI will respond to interruptions of the parallel current path first above described, incident to the action of the insulating actuator 97 in moving the contact 91 away from the contacts 93 and 95.

After completing use of the dial 51, the cover 41 should be returned to its closed position.

If it is desired to connect a portable telephone set in the outside circuit, the cover 41 should be moved toward open position until the locating catch 99 engages the cooperating depression in the cam 61.

Such positioning of said cam will cause the cylinder 75 to be positioned as indicated by the dotted circle b in Fig. 6, where said cylinder is disengaged both from the contacts 79, 79, and the contacts 77, 77.

Such positioning of the cylinder 75 interrupts the normally effective shunt path around the jacks 81 and 83, so that the entire line circuit will now traverse these jacks.

The telephone set plug may now be inserted in the portal of either of said jacks, and telephonic communication may then be effected, provided that the fire alarm circuit is unimpaired.

When a telephone set has thus been plugged into one of the jacks, if it is found that the circuit is open, the cover 41 should be moved toward or to its fully open position; thereby causing the cylinder 75 to move into engagement with the contacts 77, 77, and thereby establish a ground connection between said jacks 81 and 83.

Following establishment of such ground connection, the unimpaired portion of the circuit may be found and utilized by inserting the telephone set plug in, say, jack 81; and, if no current path is thus established, then inserting the plug in the other jack.

Thus, for example, if the line circuit is ruptured between stations S1 and S2, plugging of a telephone set into a jack 81 will not establish an effective circuit to the headquarters. However, if a telephone set is plugged into a jack 83, a circuit effective for telephonic communication will be established from a terminal of battery NB through line signal manifesting instrument LI, thence through jack 83 and the telephone set plug therein, thence through contacts 93, 91 and 95, through one of the contacts 77, cylinder 75, and the other contact 77, thence through the station ground connection and the earth to headquarters ground connection, through battery GB, and then to the other terminal of battery NB.

It should be noted that the location-code transmitters T' and T'' shown in Fig. 6 are schematically indicated as being of the so-called "closed circuit code wheel type" (e. g., the circuit is momentarily broken for signal strokes, but is otherwise closed between strokes) and no non-interference feature is indicated at these stations; it being assumed that the ground connection at a given station is rendered effective throughout signaling activity of that station. However, embodiments of this invention such as otherwise shown by Fig. 6, may also be used in connection with transmitting stations having non-interference feature and open type code wheels such as

the mechanisms schematically indicated in Fig. 14 at T' and T''.

If the transmitting mechanisms at the signaling stations of the system of Fig. 6 have non-interference, succession, and emergency ground applying features such as provided by my aforementioned Patent No. 1,999,859, some confusion in manifestation of the signal of an active one of such stations may result from utilization of the special signal formulating facilities indicated in Fig. 6 in the manner hereinbefore set forth at a time when a location-code signal is being formulated. Although such confusion might be deemed unobjectionable in fire alarm systems in which box circuit signals are received at a central office and from there retransmitted to the fire houses, the opportunity for such confusion is likely to be found objectionable where box circuit signals are received at the fire houses directly from the box circuits.

For example, assuming that the location-code transmitter at station S2 embodies a conventional type of non-interference mechanism, and is equipped with a so-called "open circuit code wheel" (e. g., the circuit being momentarily closed for signal strokes during signalling activity, but otherwise open between strokes) the opening of the cover 41 of station S1, and the actuation of the dial 51 thereat, would not cause suspension of effective formulating activity at station S2, unless and until the circuit happened to be open at the contacts 91, 93 at a time when the active transmitting mechanism attempted to close the circuit. Thus, the signal of station S2 would cause response of instruments EI and LI until the cover 41 of station S1 is opened. Response of such instruments would be suspended while such cover is open, but instrument GI would respond to the insuring portion of the signal of station S2, while instrument LI would respond to the special call of station S1, and would be unaffected by the signal of the station S2 so long as the cover 41 remained open. However, were the signal of station S2 in course of formulation when the cover 41 of station S1 is reclosed, instrument LI would thereafter respond to the remaining portion of the signal of station S2.

During the operating conditions outlined in the foregoing example, current paths would be established as follows:

During the formulation of the signaling station S2, prior to opening of the cover 41, there would be a current path from one terminal of battery NB, through line signal manifesting instrument LI, to parallel current paths one of which includes one of the contacts 79, the cylinder 75 (the cylinder 75 being positioned as shown in Fig. 4), and the other contact 79; the other of which parallel paths includes the spring jack 83, the contacts 93 and 91, and the spring jack 81. From the junction between these parallel paths current would flow through the signal formulating contacts of station S1 through the formulating contacts of station S2, and thence through the rectifier IR'', and receiving line signal manifesting instrument EI; to the other terminal of battery NB; the alternative path through receiving instrument GI being blocked in this direction by the rectifier IR'.

Opening of the cover 41 results in positioning the cylinder 75 as indicated in Fig. 5 (as also indicated by dotted line c in Fig. 6) whereupon two parallel current paths will be provided from the battery GB, one of which paths includes the battery NB, the instrument LI, the jack 83, the con-

tacts 93, 91 and 95, one of the contacts 77, the cylinder 75, the other contact 77, the ground connection at station S1 and the earth therefrom to the ground connection at the central office, and thence to the other terminal of battery GB.

The other parallel current path extends from said first named terminal to battery GB, through the instrument GI and the rectifier IR' (the alternative path through instrument EI being blocked in this direction by the rectifier IR'') and from the rectifier IR', to the signal formulating contacts of station S2 and through these contacts to the ground connection at said station (the path from said contact to said ground connection being established through the signaling activity as already explained) from the ground connection at station S2, through the earth and ground connection at central office to other terminal of battery GB.

From the foregoing, it will be evident that, after the cover 41 has been opened, the instrument LI will respond only to signals formulated by the contacts 93, 91 and 95; and the instrument GI will respond only to signals formulated by the station S2.

It will further be evident that, upon subsequent closing of the cover 41 at station S1, the instrument LI will again be brought into responsive relationship to the formulating contacts of station S2.

Furthermore, if the location-code transmitters T' and T'' were both of the non-interference and open circuit code wheel type, the continuing signal from transmitter T'' might prevent the signal of transmitter T' from immediately following the special call which was sent while the cover 41 of station S1 was open.

Description, Figs. 7-14

The embodiment of this invention indicated in Figs. 7 through 14 is specially suited for use in connection with transmitting stations having non-interference, succession and emergency ground applying features, although this embodiment might be advantageously used in connection with transmitting stations which are not equipped with the aforesaid features.

The principal differences between the embodiment of this invention shown by Figs. 1-6 (as thus far described in detail) and the embodiment shown by Figs. 7-14, are as follows:

The functions of the lever 63 are here divided between the levers 63' and 63'', which carry the rollers 73' and 73'', and the contact cylinders 75' and 75'', respectively.

The rollers 73' and 73'' are engaged by side-by-side parts of the periphery of the cam portion 65.

The cam portion 61' has slots 67' and 67'' formed in the respective sides thereof for receiving the rollers 73' and 73'', respectively (see dotted lines Fig. 7).

Walls 69' and 69'' at the inner side of said slots 67' and 67'' provide continuations of the periphery of the cam 65, and the slot walls 71' and 71'' provide internal cam surfaces for said rollers 73' and 73''.

The parts are so proportioned that the cylinder 75' is spaced away from the contacts 77, 77 when the cover 41' is fully closed, and engages said contacts when said cover is open at least until the catch 99' is effective (see Figs. 9, 10, 12 and 13).

The proportioning of the parts is further such that said cylinder 75'' engages said contacts 79',

79'', only when said cover 41' is fully closed or is open not substantially more than to the extent which renders the catch 99' effective (see Figs. 8, 9, 11 and 12).

5 The impulse sender contacts 55' (see Figs. 7 and 14) comprise a flexible contact 91' which is ordinarily spaced away from the relatively fixed contacts 93' and 95'. Said contact 91' is subject to actuation by the insulating actuator 97' for effecting momentary closures between said contacts 91', 93' and 95'.

10 By further reference to Fig. 14, it will be seen that the portion of the outside circuit which extends toward instrument LI is connected to the portal terminal 87 of jack 83', and that the flexible (or tip) terminal 86 of said jack is connected to the like terminal 86 of jack 81'; while the portal terminal 85 of jack 81' is connected to signal formulating contact 93' and to the other shunting contact 79'. Signal formulating contact 95' being connected to the transmitter Tn'.

15 The jacks 81' and 83' are equipped with grounding contacts 84, 84, which contacts are so associated with the flexible contacts 86 and 86 that when either of said flexible contacts is displaced by the insertion of an intended plug, such flexible contact will be brought into engagement with the associated grounding contact 84, in addition to being moved away from the normally engaged shunting contact, as in the instance of jacks 81 and 83 of Fig. 6.

20 The formulating contact 91', together with the jack contacts 84, 84, is connected to one of the flexible contacts 77, and the other of said contacts 77 is connected to the ground or other common return conductor.

Operation, Figs. 7-14

25 As in the case of the embodiment of this invention shown by Figs. 1-6, the outer door 23 and the cover 41' are normally closed; so that the cam 61', acting through the levers 63' and 63'' causes the cylinder 75' to be positioned away from the contacts 77, 77, and the cylinder 75'' to be positioned in engagement with the contacts 79'', 79'' (see Figs. 8 and 11).

30 While the parts are thus positioned, there is a current path from a terminal to the battery NB, through line signal manifesting instrument LI, through jacks 83' and 81', one of the contacts 78', cylinder 75' and the other contact 79', through code signal formulating contacts of transmitters Tn'' and Tn', through rectifier IR'' and instrument EI, to the other terminal of battery NB; the path through instrument GI being blocked to current in this direction by the rectifier IR'.

35 If the cover is moved to open position, as indicated in Fig. 10, the cam 61' will act through the lever 63' to move the cylinder 75' into engagement with the contacts 77, 77 (thereby to prepare a ground path from formulating contact 91' and contacts 84, 84) and said cam 61' will further act through the lever 63'' to carry the cylinder 75'' away from the contacts 79'', 79'', thereby to interrupt the current path which ordinarily provides a shunt around the contacts 93', 95'.

40 As much as the contacts 93' and 95' are ordinarily separated, interruption of the shunt around said contacts will open the associated outside circuit.

45 Assuming that all location-code transmitters (such as those exemplified at Tn', Tn'') have

non-interference features, such interruption of the associated circuit will result in suspension of signal formulation by any such transmitter which may be active when the cover 41' is opened; and such suspension will be maintained until after said cover has been reclosed, other than in a contingency which will be hereinafter described in greater detail.

From the foregoing, it will be seen that actuation of the dial 51 (which can be accomplished only while the cover 41' is in open position) will cause a series of brief grounded circuit closures, resultant from actuation of the contact 91' by the actuator 97' for the expression of the desired signal.

Parallel current paths will be established, incident to each of such grounded circuit closures, as follows:

One of said paths will extend from a terminal of battery GB, through the battery NB and the line signal manifesting instrument LI, the spring jacks 83' and 81', the contacts 93' and 91', one of the contacts 77, the cylinder 75' the other contact 77 and the ground connection at station S1', thence through the earth and the central office ground connection to the other terminal of battery GB (the ordinarily established shunt around the contacts 91' and 93' being now interrupted, because of withdrawal of the cylinder 75'' from between the contacts 79'', 79'').

The other of said parallel paths extends from said first named terminal of battery GB, through line signal manifesting instrument GI and rectifier IR' (the current path through instrument EI being blocked in this direction by the rectifier IR'') thence through code signal formulating contacts of transmitters Tn'' and Tn', through contacts 95' and 91', one of the contacts 77, the cylinder 75', the other contact 77, the ground connection at station S1', thence through earth and central station ground connection to the other terminal of battery GB.

After a special call has been thus transmitted, the location-code of the station to which response should be made can be transmitted by supplemental manipulation of the dial 51, thereby assuring that such response will be to the desired location.

In this connection it should be noted that if the location-code transmitter of the same station were relied upon in such a case, there would be possibility that the corresponding transmitter of some other station would intervene, and thereby cause misdirection of response which might have disastrous consequences.

For example, if a special call has been transmitted from station S1, and the cover 41' is thereupon closed, and the starting handle 35 of that station is then operated, there would be opportunity for a timely start to have been effected of the transmitting mechanism of station S2 such that it would prevent the signal of the transmitter Tn' of station S1 from immediately following the special call, and thereby cause misdirection of response.

Furthermore, there are occasions when the location-code mechanism at a station is already acting at a time when it is needful to send a special call therefrom. In such a case, opening of the cover 41' of such station will result in suspension of the effectiveness of the formulating action of such transmitter, and will insure unimpaired response of the central station instruments (such as GI and LI) to the special call

and to such location-code as may be supplementally transmitted by the dial 51.

Should the outside circuit be ruptured at one side or the other of a station from which a special call is transmitted in the manner just explained, such call will nevertheless be responded to by whichever of the instruments GI or LI is associated with the portion of the circuit which is unimpaired.

There is possibility that a transmitting station (such as described by my aforementioned Patent No. 1,999,859) will apply its emergency ground connection and proceed with formulation of its location-code signal in the event that, while any cover 41' is open, no signaling impulses are formulated from the dial 51 associated with such open cover for a time longer than that required for one revolution or "round" of the code wheel of such station. However, unless there is such an extended time of dial inactivity, such a station will not start or resume location-call formulation.

If it is desired to connect a portable telephone set in the circuit of an embodiment of this invention such as shown in Fig. 14, the plug associated with such set should be inserted in the portal of one or the other of the jacks 81', 83'; whereupon telephone communication may be effected provided the exterior circuit is unimpaired. If, however, it is found that the circuit is open, when a seat is thus plugged in one jack or the other, the cover 41' should be moved toward open position until the locating catch 99' engages the depression in the cam 61' provided for cooperation therewith.

The resultant positioning of said cam will cause the cylinder 75' to be moved into engagement with the contacts 77, 77, while leaving the cylinder 75'' engaging the contacts 79', 79' (see Figs. 9 and 12); thereby to prepare a ground connection with contacts 84, 84, while maintaining a shunt around the open formulating contacts 93', 95' through the shunting contacts 79', 79'.

Following preparation of such ground connection, the unimpaired portion of the circuit may be found and utilized by inserting the plug in one jack after the other, until a current path is thereby established.

If circumstances of use are such that there is no occasion for utilizing portable telephone sets, the other features of this invention may be utilized without spring jacks (such as 81 and 83). Correspondingly, other features of this invention might, under certain circumstances, be advantageously used without the provision of a cover (such as the cover 41') for the transmitter dial 51; manually operable facilities, other than said cover, being then provided for causing actuation of conditioning contacts.

While, in the foregoing, I have resorted to considerable detail of structure and association of parts in describing examples of my invention, I wish it to be understood that I have done so merely to facilitate understanding of my invention and that I do not limit my invention to such details other than as set forth in the annexed claims. On the contrary, various changes and substitutions may be made, and parts may be added to or omitted from those I hereinbefore described, without departing from the broader aspects of this invention.

It is also to be understood that the language used in the following claims is intended to cover

all of the generic and specific features of the invention herein described and all statements of the scope of the invention, which, as a matter of language, might be said to fall therebetween.

What I claim and desire to secure by Letters Patent of the United States is:

1. A signal station including a signal box, a manually operable variable signal impulse sender means including a dial in said box for selectively effecting formulations of diverse groups of code signalling impulses, a cover carried by said box positionable for obstructing manual operation of the dial of said sender means, conductors providing three circuits, said sender means including signal formulating contacts responsive to actuation of said dial having connections with said circuits and adapted to govern interconnection therebetween, a switching means connected into said contacts and said circuits, and means actuated by movement of the cover to different positions for in turn actuating the switching means to different positions, the connections between the circuits and the switching means being effective when the cover is in an obstructive position with respect to the dial of the signal sender means for assuring interconnection between two of said circuits while isolating the third circuit therefrom, said switching means including means effective when the cover is in an unobstructive position with respect to said dial for rendering interconnections between all three circuits dependent upon the closing of said formulating contacts.

2. A signal station as claimed in claim 1 characterized in that said signal formulating contacts are normally open, and said dial is a finger hold dial.

3. A signal station including a signal box, a manually operable signal sender means in said box for selectively effecting formulations of diverse groups of code signaling impulses, a cover carried by said box positionable for obstructing manual operation of said signal sender means, conductors providing a normally closed main circuit and a normally isolated branch circuit, said sender means including normally closed signal formulating contacts having connections with said circuits and adapted to govern both the continuity of said main circuit and the interconnection of said branch circuit therewith, spring jacks serially connected in said main circuit with at least one jack in each of portions of the circuit at the respective sides of said contacts, a switching means connected into said circuits, and means actuated by movement of the cover to different positions for in turn actuating the switching means to different positions including the isolation of said branch circuit from said contacts, the connections between the circuits and the switching means being effective for providing a shunt for the main circuit around said jacks and contacts when the cover is in an obstructive position with respect to the signal sender means, for interrupting said shunt when the cover is in an intermediate position, and for rendering continuity of said main circuit and interconnection of said branch circuit therewith dependent upon closures of said contacts only during unobstructive positionings of said cover with respect to said sender means.

4. A signal station including a signal box, a manually operable signal sender means in said box for selectively effecting formulations of diverse groups of code signaling impulses, a cover

carried by said box positionable for obstructing manual operation of said signal sender means, conductors providing a normally closed main circuit and a normally isolated branch circuit, said sender means including signal formulating contacts having connections with said circuits and adapted to govern both the continuity of said main circuit and the interconnection of said branch circuit therewith, spring jacks serially connected in said main circuit, a switching means connected into said circuits, means actuated by movement of the cover to different positions for in turn actuating the switching means to different positions, the connections between the circuits and the switching means being effective only when the cover is in an unobstructive position with respect to the signal sender means for the interconnection of the branch circuit either through said formulating contacts or through said jacks, and means for yieldably retaining said cover in an intermediate position for effecting circuit conditions differing from those established either during fully obstructive or fully unobstructive positionings of said cover with respect to said signal sender means.

5. A signal station including a signal box, a manually operable signal sender means in said box for selectively effecting formulations of diverse groups of code signalling impulses, a cover carried by said box positionable for obstructing manual operation of said signal sender means, conductors providing a normally closed main circuit and a normally isolated branch circuit, said signal sender means including normally open signal formulating contacts having connections with said circuits and adapted to govern both the continuity of said main circuit and the interconnection of said branch circuit therewith, spring jacks each comprising a pair of normally engaged contacts and a third contact normally separated therefrom, one of the contacts of said pair being adapted to be moved away from the other contact of said pair and into engagement with said third contact upon the insertion of a plug into the jack, conductors serially connecting two of said signal formulating contacts and the normally engaged contacts of said jacks in said main circuit, a switching means connected into said circuits, and means actuated by movement of the cover to different positions for in turn actuating the switching means to different positions, the switching means including means for connecting said branch circuit both with said signal formulating contacts and with said third contacts of the jacks only during unobstructive positionings of said cover with respect to said signal sender means and for providing a shunt for said main circuit around said signal formulating contacts only during fully obstructive positioning and during an intermediate positioning of said cover with respect to said signal sender means.

6. A signal station including a signal box, a manually operable signal sender means in said box for selectively effecting formulations of diverse groups of code signaling impulses, a cover carried by said box positionable for obstructing manual operation of said signal sender means, conductors providing a normally closed main circuit and a normally isolated branch circuit, said signal sender means including a finger hold dial and signal formulating contacts responsive to the actuation of said dial having connections with said circuits and adapted to govern both the continuity of said main circuit and the interconnec-

tion of said branch circuit therewith, spring jacks serially connected in said main circuit, a switching means connected into said circuits, and means actuated by movement of the cover to different positions for in turn actuating the switching means to different positions, the connections between the branch circuit and the switching means being effective for the interconnection of the branch circuit either through said formulating contacts or through said jacks only when the cover is in an unobstructive position with respect to the signal sender means.

7. A signal station including a signal box, a manually operable signal sender means in said box for selectively effecting formulations of diverse groups of code signaling impulses, a cover carried by said box positionable for obstructing manual operation of said signal sender means, conductors providing a normally closed main circuit and a normally isolated branch circuit, said signal sender means including a finger hold dial and normally closed signal formulating contacts having connections with said circuits and adapted to govern both the continuity of said main circuit and the interconnection of said branch circuit therewith, said signal formulating contacts being responsive to the actuation of said dial, spring jacks serially connected in said main circuit with at least one jack in each of portions of the circuit at the respective sides of said contacts, a switching means connected into said circuits, and means actuated by movement of the cover to different positions for in turn actuating the switching means to different positions, the connections between the circuits and the switching means being effective for isolating said branch circuit from said contacts and for providing a shunt for the main circuit around said jacks and contacts when the cover is in an obstructive position with respect to the signal sender means, for interrupting said shunt when the cover is in an intermediate position and for rendering continuity of said main circuit and interconnection of said branch circuit therewith dependent upon closures of said contacts only during unobstructive positionings of said cover with respect to said sender means.

8. A signal station including a signal box, a manually operable signal sender means in said box for selectively effecting formulations of diverse groups of code signaling impulses, a cover carried by said box positionable for obstructing manual operation of said signal sender means, conductors providing a normally closed main circuit and a normally isolated branch circuit, said sender means including impulse formulating contacts having connections with said circuits and adapted to govern both the continuity of said main circuit and the interconnection of said branch circuit therewith, spring jacks serially connected in said main circuit, a switching means connected into said circuits, means actuated by movement of the cover to different positions for in turn actuating the switching means to different positions, the connections between the circuits and the switching means being effective for the interconnection of the branch circuit either through said formulating contacts or through said jacks when the cover is in an unobstructive position with respect to the signal sender means and for providing a shunt for the main circuit around said contacts when the cover is in an obstructive position with respect to the signal sender means, and means for yieldably

retaining said cover in an intermediate position for effecting circuit conditions differing from those established either during fully obstructive or fully unobstructive positionings of said cover with respect to said signal sender means.

9. A signal station including a signal box, a manually operable signal sender means in said box for selectively effecting formulations of diverse groups of code signaling impulses, a cover carried by said box positionable for obstructing manual operation of said signal sender means, conductors providing a normally closed main circuit and a normally isolated branch circuit, said signal sender means including normally closed signal formulating contacts having connections with said circuits and adapted to govern both the continuity of said main circuit and the interconnection of said branch circuit therewith, spring jacks serially connected in said main circuit with at least one jack in each of portions of the circuit at the respective sides of said contacts, a switching means connected into said circuits, means actuated by movement of the cover to different positions for in turn actuating the switching means to different positions, the connections between the circuits and the switching means being effective for isolating said branch circuit from said contacts and for providing a shunt for the main circuit around said jacks and contacts when the cover is in an obstructive position with respect to the signal sender means, for interrupting said shunt when the cover is in an intermediate position, and for rendering continuity of said main circuit and interconnection of said branch circuit therewith dependent upon closures of said contacts only during unobstructive positionings of said cover with respect to said sender means, and means for yieldably locating and retaining said cover in said intermediate position.

10. A signal station including a signal box having an outer door and an inner door, a signal sender means including a finger hold dial mounted upon the outer side of said inner door, conductors providing a normally closed main circuit and a normally isolated branch circuit, said signal sender means including signal formulating contacts located inside the inner door and having connections with said circuits and adapted to govern both the continuity of said main circuit and the interconnection of said branch circuit therewith, said signal formulating contacts being responsive to the actuation of said dial for selectively effecting formulations of diverse groups of code signaling impulses, a cover hinged to the outer side of said inner door and positionable for obstructing manual operation of said dial, spring jacks serially connected in said main circuit carried by said inner door and accessible from the outer side thereof, a switching means connected into said circuits, means actuated by movement of the cover to different positions for in turn actuating the switching means to different positions, the connections between the circuits and the switching means being effective for the interconnection of the branch circuit either through said formulating contacts or through said jacks but only when the cover is in an unobstructive position with respect to said dial and for effecting circuit conditionings differing from those established either during fully obstructive or fully unobstructive positionings of the cover with respect to the dial when the cover is in an intermediate position, means for yieldably retaining said cover in an intermediate position, and means cooperatin with said cover and said outer door for insur-

17

ing fully obstructive positioning of said cover when the outer door is closed.
